US00D816617S

(12) **United States Design Patent** (10) **Patent No.:** **US D816,617 S**
(45) **Date of Patent:** **** May 1, 2018**

(54) **CONNECTION MECHANISM**

(71) Applicant: **Google Inc.**, Mountain View, CA (US)

(72) Inventors: **Jason Wong**, Millbrae, CA (US); **David Klawon**, Tucson, AZ (US)

(73) Assignee: **Google LLC**, Mountain View, CA (US)

(**) Term: **15 Years**

(21) Appl. No.: **29/565,064**

(22) Filed: **May 17, 2016**

(51) **LOC (11) Cl.** **13-03**

(52) **U.S. Cl.** **D13/147**
USPC **D13/147**

(58) **Field of Classification Search**

(57) **CLAIM**

The ornamental design for a connection mechanism, as shown and described.

DESCRIPTION

FIG. 1 is a perspective view of a connection mechanism showing our new the design;

FIG. 2 is another perspective view thereof;

FIG. 3 is a top plan view thereof;

FIG. 4 is bottom plan view thereof;

FIG. 5 is a side view thereof;

FIG. 6 is another side view thereof;

FIG. 7 is a front elevation view thereof;

FIG. 8 is a rear elevation view thereof;

FIG. 9 is a front elevation view thereof, as seen along line "9-9" of FIG. 3; and,

FIG. 10 is a front elevation view thereof, as seen along line "10-10" of FIG. 3.

The broken line in the drawing view represents unclaimed environment only and forms no part of the claimed design.

1 Claim, 6 Drawing Sheets
